UNITED STATES PATENT OFFICE.

OLIVIER PIETTE, OF BRUSSELS, BELGIUM.

PROCESS FOR THE TREATMENT OF GASES FROM GAS PRODUCERS.

Application filed February 26, 1921. Serial No. 448,196.

To all whom it may concern:

Be it known that I, OLIVIER PIETTE, a subject of the King of Belgium, and resident of Brussels, Belgium, have invented certain new and useful Improvements in Processes for the Treatment of Gases from Gas Producers; and I do hereby declare the following to be a full, clear, and exact description of the invention, such as will enable others skilled in the art to which it appertains to make and use the same, reference being had to the accompanying drawings, and to letters or figures of reference marked therein, which form a part of this specification.

15 This invention has for its object a process for the treatment of gases produced by the gasification of fuel in gas-producers, which makes possible owing to a rational utilization of the heat produced in the gas-producer, to obtain a working of the plant, as advantageous as possible from the calorific point of view and a complete and continuous conversion of the ammonia contained by the gas into crystallized sulphate.

20 The main idea which forms the basis of the invention and enables to obtain the above-mentioned results consists in causing the air which is to be sent under the grate of the gas-producer, to pass through the water which has served to cool the gases by spraying. The water is thus cooled and can be used again, and on the other hand the air is heated and at the same time charged with moisture which is useful for the production 25 of water gas in the gas-producer. Moreover, it is advantageous to adjust the circulation and the temperature of the water serving for the spraying of the gases in such a manner that the said water shall condense the ammoniacal salts only, that is the salts which do not distil in an aqueous solution and shall become richer and richer in ammoniacal salts by its successive passages in the apparatus for spraying the gases. After the 30 condensation of the fixed salts has taken place, the gases are sent, according to the present invention, into a closed saturator in which the sulphatation of the ammonia still contained in the gases and the crystallization of the produced ammonium sulphate take place.

In order to supply the saturator with the heat which is necessary for avoiding the dilution of the bath and always ensuring the 35 crystallization of the sulphate, the saturator may be provided with a heating device fed

with steam. The steam may be taken from the jacket of the gas-producer or from the discharge of the engines but in any case a characteristic feature of the invention consists in sending afterwards the steam into the circuit of the air which is to be sent under the grate of the gas-producer.

Moreover, according to the present invention, the water of condensation containing the fixed ammoniacal salts, concentrated by their successive passage through the gases, are used for diluting the sulphuric acids, in a receptacle placed before the saturator and in which a first formation of ammonium sulphate takes place with elimination of harmful acids which escape directly from the said receptacle without entering again into the circuit of the gases.

Other details of the invention are given hereinafter during the detailed description of a form of construction given by way of example and in the drawing which illustrates diagrammatically the whole plant.

The gas-producer 1 provided with a water jacket 2 produces gases by gasification of the fuel, which gases escape through 3 in order to traverse a heat-exchanger 4 which is traversed in the opposite direction by the air admitted through the pipe 5 and brought underneath the grate through a conduit 6.

The gases are freed from their dust and from part of their tar in the said heat exchanger, and at the same time they are cooled. They pass afterwards through 7 into one or several condensers 8 with water spraying, where the temperature and the travel of the spraying water are chosen in such a manner as to condense the fixed ammoniacal salts. From there, the gases pass 95 through 9 into a centrifugal extractor 10 for eliminating the aqueous or tarry vesicles in suspension, then into the saturator 11 containing a solution of sulphuric acid; the ammoniacal compounds contained in the 100 gases are converted into ammonium sulphate which crystallizes and is evacuated through an ejector 12 working by compressed air. Finally the gases pass into a scrubber 13 before reaching their place of utilization 105 through the conduit 14.

The spraying water of the condenser or condensers travels in a closed circuit. After it has been injected like rain through the nozzles 15, it cools the gases, it charges itself 110 with fixed salts and tarry compounds and falls into the receptacle 16. The tar is sepa-

rated in the latter tank and is evacuated through 17 whilst the less dense portion of the water flows through 18 into the lower part of the apparatus 19. In the latter apparatus the water is subjected to bubbling from the air which is compressed by a fan 20 and is injected by means of a suitable device 21. The air is thus charged with moisture and gets heated while cooling the liquid; it enters then into the pipe 5 which takes it to the heat-exchanger 4 above described; the water which has been cooled is taken by a pump 22 inserted in the piping 23 which sends water to the nozzles 15.

15 When the water has been used several times for spraying and is sufficiently concentrated in fixed salts, is sent by means of a liquid-raising apparatus 25 into a receptacle 24 where it is mixed with the sulphuric acid 20 serving for the feeding of the saturator 11; there is formation of ammonium sulphate in the said acid whilst the harmful acids, more especially hydrochloric acid, escape through 26 where they could be drawn off 25 and sent into the atmosphere. It is thus seen that by this method, the harmful acids do not remain in the gases of the gas-producer and do not attack the piping and the apparatus in which they are used.

30 Owing to the large quantities of vapours carried over by the gases into the condensers 8 and of the variable percentage of the gases and ammonia it is necessary to provide a heating device for the liquid contained in the 35 saturator 11 with a view to preventing the dilution of the bath and to ensure the crystallization of the ammonium sulphate. A coil 27 is used which receives steam from a receptacle 28, which steam is superheated if necessary by its passage through a heating apparatus 29 fed with gas from the gas-producer. The steam leaving the coil 27 is sent 40 into the apparatus 19 where it serves for heating and moistening the air sent under the grate of the gas produced. The receptacle 28 receives for instance the exhaust steam coming through 30 and 31 from the engine driving the blower 20 and the extracting apparatus 10; it is also possible to bring steam coming from the jacket of the 45 gas producer through the pipe 32.

50 The water which is brought through 33 at the upper part of the scrubber 13 and which has been heated by contact with the 55 gases flows out into a receptacle 34; a portion of this water passes into the apparatus 19 in order to compensate the quantities which have been periodically taken by the liquid-raising apparatus 25 in the water 60 circuit of the condensers 8 and the losses by evaporation; the remaining portion of the water is sent into the jacket 2 of the gas producer through a pipe which is not shown.

65 It is seen that the process according to the present invention effects an important sav-

ing of the steam relatively to known processes in which the total condensation of ammoniacal bodies is effected by means of water with subsequent distillation or the condensation of the said compounds is obtained by spraying with a sulphuric solution. In the first case besides the lime an important quantity of steam is consumed in the distilling column and large quantities of residual waters are produced; in the second case it is necessary to consume steam in order to concentrate the solutions of sulphate of ammonia.

70 Moreover, in contradistinction to what happens in the known processes there is no 80 less of ammoniacal bodies to be feared.

What I claim is:

1. A process for the treatment of gases from gas-producers, comprising passing the 85 gases into condensers with spraying water, adjusting the temperature by the circulation of the water in such a manner as to condense only fixed ammoniacal salts and tarry compounds, passing said gases into a closed 90 saturator in which the remaining ammonical compounds are converted into ammonium sulphate and the said ammonium sulphate is crystallized, and placing the outlet water from the condensers in contact with air blown under the grate of the gas producer. 95

2. A process for the treatment of gases from gas producers, comprising passing the 100 gases into condensers with spraying water, adjusting the temperature by the circulation of the water in such a manner as to condense only fixed ammoniacal salts and tarry compounds, passing said gases into a closed 105 saturator in which the remaining ammoniacal compounds are converted into ammonium sulphate and the said ammonium sulphate is crystallized, placing the outlet water from the condensers in contact with air blown under the grate of the gas producer, heating the solution of the saturator by a steam circulation, and sending said steam into the 110 circuit of the air passing under the grate of the gas producer.

3. A process for the treatment of gases from gas producers, comprising passing the 115 gases into condensers with spraying water, adjusting the temperature by the circulation of the water in such a manner as to condense only fixed ammoniacal salts and tarry compounds, passing said gases into a closed 120 saturator in which the remaining ammoniacal compounds are converted into sulphate ammonium and the said ammonium sulphate is crystallized, placing the outlet water from the condensers in contact with air blown under the grate of the gas-producer, heating the solution of the saturator by a steam circulation, sending said steam into the circuit 125 of the air passing under the grate of the gas producer, and heating saturator with the exhaust steam.

4. A process for the treatment of gases from gas producers, comprising passing the gases into condensers with spraying water, adjusting the temperature by the circulation of the water in such a manner as to condense only fixed ammoniacal salts and tarry compounds, passing said gases into a closed saturator in which the remaining ammoniacal compounds are converted into ammonium sulphate and the said ammonium sulphate is crystallized, placing the outlet water from the condensers in contact with air blown under the grate of the gas producer, heating the solution of the saturator by a steam circulation from the water jacket of the gas producer, and sending said steam into the circuit of the air passing under the grate of the gas producer.

5. A process for the treatment of gases from gas-producers, comprising passing the gases into condensers with spraying water, adjusting the temperature by the circulation of the water in such a manner as to condense only fixed ammoniacal salts and tarry compounds, passing said gases into a closed saturator in which the remaining ammoniacal compounds are converted into ammonium sulphate and the said ammonium sulphate is crystallized, placing the outlet water from the condensers in contact with air blown under the grate of the gas producer, heating the solution of the saturator by a steam circulation, sending said steam into the circuit of the air passing under the grate of the gas producer, and super-heating in a heat-exchanger the steam carrier with this air.

6. A process for the treatment of gases from gas-producers, comprising passing the gases into condensers with spraying water, adjusting the temperature by the circula-

tion of the water in such a manner as to condense only fixed ammoniacal salts and tarry compounds, passing said gases into a closed saturator in which the remaining ammoniacal compounds are converted into ammonium sulphate and the said ammonium sulphate is crystallized, placing the outlet water from the condensers in contact with air blown into the grate of the gas producer, sending the water which has served to condense the fixed ammoniacal salts into a receptacle, and mixing with it the sulphuric acid supplied to the saturator, with formation of ammonium sulphate and elimination of the harmful volatile acids.

7. A process for the treatment of gases from gas-producers, comprising passing the gases into condensers with spraying water, adjusting the temperature by the circulation of the water in such a manner as to condense only fixed ammoniacal salts and tarry compounds, passing said gases into a closed saturator in which the remaining ammoniacal compounds are converted into ammonium sulphate and the said ammonium sulphate is crystallized, placing the outlet water from the condensers in contact with air blown under the grate of the gas-producer, cooling the gases which leave the saturator by spraying with water and feeding said heated water partly to the water jacket of the gas producer and partly to the air hydrators.

In testimony whereof I affix my signature in presence of two witnesses.

OLIVIER PIETTE.
